C. J. HODGE.

TANK FOR MINERAL OR ORE WASHING JIGS.

(Application filed Sept. 30, 1898.)

UNITED STATES PATENT OFFICE.

CHARLES J. HODGE, OF HOUGHTON, MICHIGAN.

DESIGN FOR A TANK FOR MINERAL OR ORE WASHING JIGS.

SPECIFICATION forming part of Design No. 29,684, dated November 15, 1898.

Application filed September 30, 1898. Serial No. 692,347. Term of patent 7 years.

To all whom it may concern:

Be it known that I, CHARLES J. HODGE, a citizen of the United States, residing at Houghton, in the county of Houghton and State of Michigan, have invented and produced a new and original Design or Useful Shape for a Tank for Mineral or Ore Washing Jigs, of which the following, in connection with the accompanying drawings, is a full, clear, and exact specification.

In the said drawings, Figure 1 is a vertical longitudinal section, partly in side elevation, taken on the line 1 1, Fig. 2, of a tank for mineral or ore wasing jigs embodying my design. Fig. 2 is a plan view thereof, and Fig. 3 is a transverse vertical section taken on the line 3 3, Fig. 1.

The leading features of my design consist of a tank for mineral or ore washing jigs having the compartments A B, the intermediate partition C, and the partitions D E.

The tank when viewed in plan, as in Fig. 1, is oblong and is divided in twain by the transverse partition C, which constitutes of the tank the two equal compartments A B, and in each of these compartments A B, respectively, appear the additional transverse partitions D E, which are located closer to the partition C than to the outer end walls of the compartments A B, so as to form with the partitions C two comparatively narrow oblong compartments opening at the bottom into the compartments A B, respectively.

The bottoms of the compartments A B converge downwardly at their contiguous sides from the partition C and at the other sides from the vertical side walls G of the tank, thus forming on the bottom of each of the compartments A B a four-sided figure tapering downwardly to a base II, arranged under each compartment A B, and being elongated transversely of the tank, as indicated in Fig. 3. On each side of each compartment is a perforated boss I, and formed in the top of the base II, on one side, is a tubular boss II'.

The ledges F appear in plan view like inclined planes extending toward the center of each of the compartments A B from the partitions D E, respectively, and are continued entirely across the tank.

The partitions C D E, as well as the edge of the tank which joins the ends of these partitions, rise slightly above the top of the tank, as shown in Figs. 1 and 3.

Having thus described my invention, what I claim as new therein, and desire to secure by Letters Patent, is—

The design for a tank for mineral or ore washing jigs substantially as herein shown and described.

CHARLES J. HODGE.
